UNITED STATES PATENT OFFICE.

BENJAMIN L. E. GOWEN, OF BOSTON, MASSACHUSETTS.

BRIDLE.

SPECIFICATION forming part of Letters Patent No. 389,701, dated September 18, 1888.

Application filed June 16, 1888. Serial No. 277,312. (No model.)

To all whom it may concern:

Be it known that I, BENJAMIN L. E. GOWEN, of Boston, in the county of Suffolk, State of Massachusetts, have invented a certain new and useful Improvement in Bridles, of which the following is a description sufficiently full, clear, and exact to enable any person skilled in the art or science to which said invention appertains to make and use the same, reference being had to the accompanying drawings, forming part of this specification, in which—

Figure 1 is a perspective view showing a bridle embodying my improvement in use; Fig. 2, an enlarged plan view of the crown-piece detached, and Fig. 3 a like view showing the crown-piece without branch billets.

Like letters and figures of reference indicate corresponding parts in the different figures of the drawings.

20 The crown-piece of a bridle, as ordinarily constructed, consists of a straight leather strap, which passes over the head of the horse behind the ears, and to which the brow-band, cheek-straps, and throat-latch are secured. 25 When formed in this manner the crown-piece constantly presses against the rear portion of the base of the ear, thus tending to expand it and magnify or exaggerate sound as heard by the horse. It also prevents the ear from moving freely, and being constantly pressed against it, as described, is liable to gall the ear and produce sores, thus causing the horse much pain and sometimes rendering him irritable and balky.

30 My invention is designed to obviate these objections, and to that end I make use of means which will be readily understood by all conversant with such matters from the following explanation:

35 In the drawings, A represents the crown-piece of the bridle, B the throat-latch, C the cheek-strap, and D the brow-band, the throat-latch, cheek-strap, and brow-band being all of the ordinary form and construction.

40 The crown-piece consists of a strap, prefer-

ably composed of leather, and having a straight body or central portion, x (see Fig. 2,) adapted to rest on the crown of the head between the ears of the horse. At each side of the straight portion x is a semicircular or curved portion, 50 z, which passes around the base of the horse's ear, said strap being provided at each end with a "billet," v, to which the ordinary throat-latch B is secured, the pull of said latch being nearly in a direct line with the portion 55 x, thus preventing the crown-piece from being forced against the ears of the horse by the action of the checkrein K, which passes through a loop in the latch B in the usual manner, or from any other cause. On the rear edge of 60 each curved portion z, near its outer end, there is a diagonally-arranged branch billet, b, to which a supplemental throat-latch, H, is secured, the pull of said latch being on the lines 65 from the inner corners, f f', respectively, of the curved portions z, through the centers of the billets b, thus tending to hold the crown-piece away from the ears of the horse.

In Fig. 3 the crown-piece is shown as without a branch billet, but its ends are bifurcated 70 or provided with two billets, v, to which both the cheek-strap C and the throat-latch B can be attached without employing a rosette, h, if desired. A buckle, m, is secured centrally to the body x for receiving the straps 75, leading 75 to the blinds K.

Having thus explained my invention, what I claim is—

A crown-piece for a bridle having a straight body, as x, a curved portion, as z, connected 80 with each end of said body and adapted to pass partially around the ear of the horse, and billets v b, connected with the outer end of each of said curved portions, substantially as set forth.

BENJAMIN L. E. GOWEN.
